HEAT-TREATING BASKET

Carl H. Hill, Norristown, and Harold I. Schneider, Philadelphia, Pa., assignors to The Budd Company, Philadelphia, Pa., a corporation of Pennsylvania

Application September 2, 1944, Serial No. 552,415

13 Claims. (Cl. 263—47)

1

This invention relates to heat treating baskets and has for an object the provisions of improvements in this art.

Heat treating baskets are given severe use because of repeated cycles of high heating and rapid cooling. They are loaded with metal parts and heated in a furnace to a high temperature, such as a critical temperature of cherry red for steel or the like, and then cooled in such manner as the parts require. When such baskets are made by welding their elements together, as is now common, the repeated great changes in temperature cause cracks and breaks to develop to such an extent that the baskets soon become useless.

According to the present invention a basket is provided which is of a very loose construction so as to allow free movement of expansion and contraction within reasonable limits, the parts being so designed, however, as to cause the basket to hold its shape beyond these limits of expansion and contraction.

The desired structure is largely achieved by using side standards of an improved design which have a unique connection with side elements, such as rods, and bottom elements, such as rods and bars. The construction is of such a nature that the baskets may be very rapidly assembled from a few standard parts by unskilled labor and also quickly repaired to replace one or more elements without dismantling the whole basket.

One embodiment of the invention will be described by way of example in connection with the accompanying drawings, in which:

Figure 1 is a plan view of a heat treating basket embodying the present invention;

Figure 2 is an end elevation;

Figure 3 is a side elevation;

Figure 4 is an enlarged perspective view of a corner detail;

Figure 5 is another perspective view of the corner detail;

Figure 6 is a perspective view of a side detail; and

Figure 7 is a perspective view of an end detail.

Referring to the drawings, the basket comprises corner standards or brackets 1, end brackets 2, side brackets 3, channel-shaped bottom bars 4, transverse bottom rods 5, spacers 6 on the bottom rods, and side rods 7. Generically all of the elements 4, 5 and 7 may be referred to as bars.

The rods are passed through oversized holes in the bottom bars 4 and the standards 1, 2 and

3 and are retained by washers 8 and cotter pins 9, the rods being provided with suitable holes for the cotter pins. If desired, washers and cotter pins may also be provided on some or all of the side rods 7 on each side of the standards 2 or 3, as shown in Figure 6.

Each of the standards is threaded by the several side rods 7 of at least one side and the lower end of each standard is connected with two or more bottom elements of one type and one or more bottom elements of the other type.

As shown in Figure 6, the side standards 3 are threaded by the rods 1 of one side and their lower ends are connected to two bottom bar elements 4 and are threaded by one bottom rod element 5. In plan, the side standard is U-shaped, having a wide back plate 10, a long front or outer flange 11 and a short inner flange 12. The lower ends of the flanges 11 and 12 extend alongside or into the spaces between the side walls of the channel bars 4 and the bottom rod 5 is threaded through both of the flanges 11 and 12 and the side walls of the bottom bars 4. The side rods 7 extend through the back plate 10 of the bracket.

As shown in Figure 7, the end standards 2 are threaded by the rods 7 of one side and their lower ends are connected to one bottom bar element 4 and are threaded by two bottom rod elements 5. In plan, the side standard is U-shaped having a back plate 13 and side flanges 14. The lower ends of the flanges 14 extend alongside or into the space between the side walls of the channel bar 4 and the bottom rods 5 are threaded through both of the flanges 14 and the side walls of the bottom bar 4. The side rods 7 also extend through both of the side flanges 14.

As shown in Figures 4 and 5, the corner standards 1 are threaded by the rods 1 of two sides and their lower ends are connected to two bottom bar elements 4 and are threaded by two bottom rod elements 5. In plan, the corner standard is U-shaped in part and V-shaped in part, having for the U-shaped part a back plate 15, a long side flange 16 and a short side flange 17; and having for the V-shaped part a wing 18 and a wing or flange 19. The lower ends of the flanges 16, 17 and 19 extend down alongside the side walls of the channel bars and the bottom rods 5 are threaded through the flanges and the side walls of the bottom bars. The rods 7 of one side extend through the flange 16 and the rods of the other side wall at a corner extend through the inner wing 18. The wing 18 and the flange 16 are joined at their side ex-

tremities and themselves form a reverse V at the corner whereby the rods may be positioned at common levels without interfering with each other. After the rod of one side has been inserted the rod of corresponding height of the other side may be inserted past the end of the first.

The assembly and repair procedure will be apparent from the foregoing description. The assembled device presents no parts which are not perfectly free to expand and contract in a simple linear element when heated and cooled. Also the several parts are loosely joined in order that they will not strain each other. There is no welding or jointing required for assembly. Nevertheless, because of the special shape and disposition of the standards relative to the other elements of the basket, all of the parts are securely connected together and the basket strongly retains its shape except for the liberal looseness in all directions which is provided.

While one embodiment has been illustrated and described, it is to be understood that the invention may have various embodiments within the limits of the prior art and the scope of the subjoined claims.

What is claimed is:

1. A heat treating basket comprising in combination, a plurality of side standards, a plurality of side rods connected with the upper part of each standard, and a plurality of bottom elements connected to an end of the standard, some of the bottom elements being disposed crosswise of other bottom elements.

2. A heat treating basket comprising in combination, a plurality of side standards, one or more bottom elements of a first type connected with one end of each standard, and two or more bottom elements of a second type connected with the same end of the standard, said bottom elements of the two types being connected with each other.

3. A heat treating basket comprising in combination, a plurality of side standards of U-shape, a plurality of side bars connected with the upper part of each standard, and a plurality of transversely arranged bottom bars connected with the end of each standard, there being at least two bottom bars running in the same direction connected with the ends of the standards.

4. A heat treating basket comprising in combination a plurality of side standards, a plurality of side bars threaded through holes in the standards, at least one bottom bar threaded through holes in the standards, and at least one transversely disposed bottom bar connected to the standard by the first said bottom bar.

5. A heat treating basket as set forth in claim 4, in which one of said bottom bars is channel-shaped, and in which said standards have at least one flange end disposed alongside a side wall of the channel-shaped bar.

6. A heat treating basket as set forth in claim 4, in which one of said bottom bars is channel-shaped, and in which said standards have at least one flange end disposed within the interior of the channel-shaped bar.

7. A heat treating basket as set forth in claim 4 in which the bottom bars running in one direction are channel-shaped, and in which said standards are U-shaped and have at least one flange end disposed within the interior of a channel-shaped bar.

8. A heat treating basket comprising in combination, a plurality of corner standards having connected sides with an inwardly disposed corner, side rods of two adjacent sides extending through the adjacent sides of a standard, and crossing bottom elements connected with the bottom of each standard.

9. A heat treating basket comprising in combination, a plurality of standard shaped corner standards each of U-V-section shape, the V-section presenting the point of the V diagonally inward and the U-section presenting its open side parallel to the length of one side of the basket, a plurality of coordinately arranged side bars loosely connected with each standard, and a plurality of coordinately arranged bottom bars loosely connected with the bottom of each standard and with each other.

10. A heat treating basket comprising in combination, a plurality of U-shaped side standards, a plurality of side rods loosely threaded through said standards to form an enclosure, a plurality of parallel channel-shaped bottom bars having the open side upward, a plurality of bottom rods threaded through the side walls of said channel bars, said standards having flange ends disposed alongside the sides of certain of said channel bars, and said bottom rods also being threaded through holes in the ends of said standard flanges, all of said rods having loose-fitting retaining means on their ends.

11. A heat treating basket comprising in combination a plurality of corner standards having reversed outwardly diverging V-shaped plates, and basket side rods passing through and attached to each section of said V-shaped plates.

12. A heat treating basket comprising in combination a plurality of corner standards having reversed outwardly diverging V-shaped plates, basket side rods passing through and loosely attached to each section of said V-shaped plates, and base bars attached to said V-shaped plates and side rods.

13. A heat treating basket comprising in combination a plurality of corner standards having reversed outwardly diverging V-shaped plates, a side plate secured to one section of each of said plates, an angle plate secured to the other section of said plates, and basket side rods passing through and attached to each of said V-shaped plate sections, side plates and angle plates of said corner standards.
